FRITZ WEVER, OF STUTTGART, GERMANY, ASSIGNOR, BY MESNE ASSIGNMENTS, TO
THE CHEMICAL FOUNDATION, INC., A CORPORATION OF DELAWARE.

MACHINE FOR MAKING LAYER FABRICS.

1,392,287.

Specification of Letters Patent. Patented Sept. 27, 1921.

Application filed October 29, 1918. Serial No. 260,214.

To all whom it may concern:

Be it known that I, FRITZ WEVER, residing at Stuttgart, in the Kingdom of Wurttemberg, Germany, have invented certain new and useful Improvements in Machines for Making Layer Fabrics, for which I have filed application in Germany, W 50111 X 13 b, June 13, 1917, of which the following is a specification.

My invention relates to apparatus for making layer fabrics, such apparatus being designed in particular for the manufacture of heat-non-conducting fabrics or linings in which one or more layers of feathers are superimposed on a web of woven or other material or interposed between two such layers. The feathers which according to the character of the fabric to be produced, may be of various kinds, from the softest down to striped wing feathers, are spread over the inclosing fabric serving as a carrier in an even flat uniform layer and in an irregular manner as regards the direction of the individual feathers. The carrying fabric is then fed to the means for securing the feathers to the carrying fabric, such as a sewing or pasting apparatus. A second covering layer may be superimposed on the layer or layers of feathers where the combined fabric is to serve as a lining or for a quilted garment.

An apparatus embodying my invention for this purpose comprises means for properly conveying, loosening and spreading the feathers in an even uniform and flat layer on the fabric or between the fabrics to which they are to be secured. Since the feathers have a tendency to aggregate or form in masses and to adhere to the parts of the apparatus my invention provides means for loosening, separating and positively advancing the same, also for counteracting the tendency to lag behind, due to the lightness and resiliency of the material. Provision is also made that the arrangement of the feathers, when spread on the supporting web, will not be disturbed before the securing mechanism has acted.

The device for feeding or spreading the feathers to the apparatus may be arranged to feed a single layer of feathers from the

feather-supplying receptacle on to the supporting fabric, or to supply two or more such layers, each of which is preferably fed from a separate and independent receptacle. After such spreading of the feather-layer or layers the same are secured in position by further feeding the fabric with the superposed feather-layer or the fabrics with the interposed layer or layers of feathers to the securing apparatus. In the case of a plurality of feather-layers, I preferably arrange a bottom layer of fine downy material, such as down or plucked breast feathers, while the upper layer is made to consist of coarser material, such as striped wing feathers.

An essential feature of the invention consists in the means for feeding forward the feathers from a receptacle by an air current, distributing means, for then taking them up and advancing them in an evenly and finely divided and loose condition which distributing means serve to carry them forward to a point whence they are conveyed to a spreader, while still in a loose condition, by means of another air current, said spreader also performs the work of directing them upon the web of material to which they are to be secured.

Other features and details of the invention will be apparent from the following detailed description and from the claims.

In the accompanying drawing I have illustrated what I consider the preferred manner of carrying out my invention.

In this drawing—

Fig. 1 represents a longitudinal sectional elevation of a machine embodying my invention;

Fig. 2 a top plan of the same, partially in section;

Fig. 3 a detail view in perspective of parts of the feather distributor;

Figs. 4 and 4^a another detail view in elevation, partly broken away, and sectional plan, respectively, of the receiving portion of the feather distributor;

Figs. 5 and 5^a detail views of intermittent gearing forming part of the feed mechanism in side elevation and plan, respectively;

Fig. 6 a detail view in sectional perspective of the forward portion of the spreading conduit;

Fig. 7 a further detail view;

5 Figs. 8 and 8^a enlarged detail views in side elevation and plan, respectively of the spreader casing;

10 Figs. 9, 10 and 11 detail views in cross section and in longitudinal section, respectively, of the friction clutch transmission device for actuating the spreader and distributor;

15 Fig. 12 a longitudinal sectional elevation of the distributing portion of a somewhat modified form of apparatus;

Fig. 13 a detail view of same on line 13—13 of Fig. 12;

20 Fig. 14 a sectional side elevation of a modified form of apparatus embodying my invention and

Fig. 15 a sectional top plan of the same.

In all the figures the same parts are designated by the same reference characters.

Referring first to Figs. 1, 2 and 3, it is to be observed that at A is represented a feather distributing device to which the feathers are fed from a feather bin or container through a conduit 1 by means of an air blast A' and whence they are conveyed by a second blast 30 A² to a spreading device B, which serves to deposit them in an even uniform layer on the supporting web or fabric F of suitable textile material, paper or equivalent material and between it and the second upper web or 35 fabric F', the webs or fabrics with their interposed layer of feathers thence passing to the feather securing or fastening device, in the present instance consisting of a sewing or quilting machine C of any suitable construction.

40 The feather distributing device comprises means for conveying, loosening and separating the feathers and positively advancing them to the blast A², which conveys them to the spreading device B, and will be now described in detail.

Under the influence of the blast from A' the feathers proceed through pipe a in tangential direction into the hopper 8, Figs. 1, 50 4 and 4^a. The tangential relation of pipe a to the hopper 8 is best shown in Figs. 4 and 4^a. As shown in Figs. 1 and 4, the said hopper is provided at its top with a vent pipe 9 provided with a cap 9^a provided with 55 a perforated top which is here shown as formed of wire cloth or otherwise reticulated material. The vent-pipe 9 descends concentrically into the hopper so that its lower end is at a short distance below the 60 inlet-pipe a, thereby forcing the feathers to circulate concentrically around the vent-pipe before descending to the lower tapering part of hopper 8, the excess of air from the blast coincidentally escaping through the vent-pipe. 65 From the hopper 8 the feathers drop into the

distributer proper or feather receptacle 7 by a chute 8^a, which at its lower portion 7^a, is rectangular in horizontal cross-section and is formed as a casing for the stripping mechanism for separating and loosening feathers 70 from the mass descending through the hopper. By reference particularly to Fig. 3 it will be noted that the rectangular portion of the hopper is open at its sides said open sides being provided with grate-bars 6 secured to 75 the vertically adjustable rectangular frame 6^a embracing the rectangular portion 7^a of the hopper, said frame 6^a being provided with a depending slotted tongue engaged by a clamp-screw 6^b threaded into the hopper 80 wall. By loosening said screw the frame 6^a and with it the grate-bars 6 may be suitably adjusted vertically and then secured in any position of adjustment, so as to extend more or less into the upper portion of the feather 85 receptacle.

Within the casing of the distributer proper 7 and below the hopper is arranged a pair of downwardly convergent chain conveyers and separators, each consisting of a pair of 90 chains 2, 2, each running over a pair of sprocket wheels or pulleys 2^a, 2^a and connected at suitable intervals with cross-bars 2^b, best shown in the detail view of Fig. 7, each of said cross-bars 2^b being provided 95 with loosening and separating forks 3 mounted on stems 3^a secured perpendicularly to the chains, as best seen in Fig. 1. The lower sprocket-wheels are less in diameter than the upper ones. Thereby the conveying forks in their lower path are rapidly thrown from a horizontal to a vertical depending position, and are thus caused to tear apart cohering masses of feathers and to throw them off more readily. The inner 100 portions of the chains travel from the middle of the receptacle upward and then downward and outward thus carrying the feathers from the downwardly tapering funnel-shaped space between the chains upward 110 and then downward along the walls of the casing, as indicated by the arrows.

Below the grate bars 6 and opposite the path of the forks 3 are arranged the regulating rakes 5, 5^a, which serve to remove 115 portions of the charge of forks which have received an excessive quantity of feathers and to supply them to forks not sufficiently charged, as they pass the rakes. These rakes thus act as charge-regulators.

120 The lower the ends of the adjustable grate-bars 6 are made to extend, the less will be the quantity of feathers received on the traveling forks 3 from the hopper and, hence the less the amount of material deposited on the web or fabric. By forming the side-walls of this part of the distributer of grate-bars, the air from the feather propelling blast is allowed to escape and thereby 125 a balling together or agglomeration of the 130

feathers is avoided and their dropping in a loose segregated condition facilitated. This result is moreover enhanced by the fact that the bars give rise to less friction than in the case of closed continuous walls. As will be noted also, the space between the oppositely arranged grate-bars is downwardly flaring, which also adds to the result of a perfect and loose downward feed of the feathers.

Below the conveyer chains 2, 2 the casing of the distributor 7 continues downward in tapering form and communicates with the transverse pipe 11 (see Fig. 2) which leads to the inner chamber of the blast or suction-blower A² (Figs. 1 and 2), which, in turn, communicates with the pipe 12 through which the feathers are by the said blast or blower A² delivered to the spreading apparatus B, to be described below. The blower A² with the distributor casing 7 is mounted on the standards 13, 13 which standards also support the intermittent gearing D (Figs. 2, 5 and 5^a) for imparting a step-by-step feeding movement to the conveying chains 2, 2.

The intermittent gear will be described in detail further on.

The blower A² leads into a conduit 12 removably connected to the spreading device B (Figs. 1, 2, 6, 8, and 8^a) by a union 14. As shown, the casing of the spreading device is flaring horizontally in the direction of the blast and vertically tapering in the same direction. Within the spreader casing are arranged the deflecting or baffle-plates 14^a and 14^b which, as indicated in Fig. 2, are angular in form with their apices pointing rearward toward the feather inlet. As shown, the deflecting plate 14^b in the forward part of the spreader casing is secured to its upper wall and extends partly down to the lower wall, while the deflecting plate 14^a is secured to the lower wall and extends partly to the upper wall. These deflecting plates serve to direct the feathers in part toward the sides of the spreader casing thus serving to evenly spread them at the mouth 14^c of the spreader casing, where they are arrested by a row of teeth of the gang of toothed disks 15^a, mounted on the delivering roller 15 arranged at the said mouth of the spreader casing. The teeth of the toothed disks are adapted to enter and pass through the longitudinal parallel slots 16 at the said mouth of the casing, said slots being best shown in the enlarged detail views of Figs. 6, 8 and 8^a. The toothed disks are rotated step-by-step in the direction indicated by the arrows, so as to advance the feather layers portion by portion or in wind-rows onto the web of fabric F and between it and the second web or fabric F', the feed rollers 17 and 17^a arranged in advance of the spreader casing acting to immediately retain the feather-layer between the two webs and to feed the combined fab-

ric to the securing device, in the present instance represented as a sewing mechanism C. As shown in Figs. 1, 8 and 8^a and more particularly, in Fig. 6, the casing of the spreader B is provided at its forward portion with ribs 14^d extending longitudinally between the slots 16 thus affording a space between the layer of feathers and the upper and lower walls of the casing at this point, whereby the air from the blast may escape. As shown in Figs. 8 and 8^a, the upper wall 14^e of the casing is hinged at 14^f its forward end being furnished with set screws 14^g, 14^g, engaging with slots 14^h, 14^h in the side walls of the casing. Thereby the width of the mouth of the casing may be regulated to conform to the thickness of the layer of feathers passing through the said casing.

The sewing mechanism is driven by the transverse sewing mechanism shaft 18 on which are mounted the fast and loose pulleys 18^a to which motion is transmitted from any suitable source of power. From the sewing mechanism shaft 18 the various parts of the apparatus are in the present embodiment of my invention actuated by the following means.

On the shaft 18 is fixed the eccentric 19 which through rod 19^a imparts an oscillating movement to the crank 20 of the friction clutch device G shown in detail in Figs. 9, 10 and 11 serving to impart an intermittent rotary movement to the shaft g from which the various parts of the apparatus are actuated. As will be noted by reference to said Figs. 9, 10 and 11 the said clutch-device comprises a cylindrical casing g' keyed to the shaft g by set-screws g². Within the casing g' is arranged the drum 21 keyed to the crank 20, loosely mounted on shaft g and provided with a number of notches or chambers 22 within each of which is seated a roller 23 impelled forward by a spring 23' and just fitting into the space formed by the notch and the inner wall of the casing g'. When the crank moves in the direction of the arrow in Fig. 9, which is a cross-section on line 9--9 of Fig. 11, looking in the direction of the arrow in said figure, the rollers 23 will be clamped between the casing g' and the seat of the roller, whereby a partial revolution is imparted to the shaft g. On the return-stroke of the crank 20 the rollers are released and the drum 21 returns to its initial position, the shaft g remaining stationary during this return-movement. In order to positively secure the said shaft against any retrograde movement, a brake-drum 24, also loosely mounted on the shaft g and secured to the shaft bearing 25 is arranged in the casing g', as shown in Figs. 10 and 11. As seen from Fig. 10, this brake-drum 24 is provided with notches 22' and spring rollers 23' similarly to the shaft-actuating clutch-device 22, 23, but with the

difference that in this case the rollers are pressed in opposite directions by the springs. By this means any tendency of the shaft to reverse its rotation on the return stroke of the crank 20 will be immediately arrested by the fact that the rollers 23' will be clamped between their seats and the casing-wall. From shaft g the movement is transmitted to the cloth-feed shaft f by sprocket wheels 26 and 27 and intermediate chain 28 and from the shaft f to the delivering roller 15 and its gang of toothed arresting disks by the sprocket-wheels 29 and 30 and the chain 31.

15 The feed chains 2, 2 and the feather separating and loosening forks 3, 3 are advanced successively and step-by-step from the shaft f by means of a chain 32 running over a sprocket wheel 33 on said shaft f and a sprocket wheel 34 which latter sprocket-wheel is keyed to the arbor 35 carrying the propelling disk 35^a of the intermittent gearing shown in plan in Fig. 2 and in detail in Figs. 5 and 5^a. From the latter two figures 20 it will be observed that the disk 35^a forms part of a double Geneva stop movement and is provided with a pin 35^b which at each semi-revolution engages a radial notch 36^a or 37^a of one of the wheels 36 or 37 thereby 25 imparting to it one-eighth of a rotation. The gearing is so arranged that the wheels 36, 37 are advanced successively, each wheel being given, in turn, an eighth revolution at every half revolution of the propelling 30 disk 35^a. The periphery of the notched wheels 36, 37 between the notches 36^a, 37^a is so formed as to fit snugly against the periphery of the propelling disk 35^a after the pin 35^b has turned it forward by one notch.

35 40 The wheel 36 is directly keyed to the arbor of the left-hand sprocket wheel 2^a (Fig. 1), while the wheel 37 is provided with a cog wheel 37^b meshing with a cog-wheel 38 mounted on the shaft 38^a of the right-hand 45 sprocket wheel 2^a. Thereby the said sprocket wheels and the conveyer chains 2, 2 with the separator-forks 3, are caused to travel from below outward, the feathers being carried from the top outward and downward 50 between the conveyer chains and the walls of the tapering distributor casing 7, as indicated by the arrows in Fig. 1. The direction of the travel of the parts of the step-by-step gearing is indicated by the arrows in Fig. 5.

In order to vary the stroke of the crank 20 and thereby the speed and rate of feed of the feathers and fabric to the sewing mechanism the said crank is provided with a slot 60 20' said slot receiving the pin 19' of eccentric rod 19^a, which pin is secured in its various positions of adjustment in the slot by the nut 19^b threaded on the end of said pin, as best shown in Fig. 11.

65 The operation of the apparatus will be

clear from the foregoing. The feathers from a bin or other receptacle are by the blower A' carried through conduit 1 into the hopper 8 whence the air escapes through vent pipe 9 the feathers being whirled by reason of the tangential ingress and thereby receiving a preliminary loosening. From hopper 8 they drop into the receptacle 7. As they pass by the grate-bars 6, 6 they are further loosened by reason of the downwardly flaring arrangement of said grate-bars and the escape of any residual compressed air from the blower through the side-openings of the conduit at this point. They are then carried upward from the middle of the receptacle by the conveying forks 3 and then downward along the outer walls of the receptacle to the pipe 11 leading to the blast A². Should any of the forks 3 be too heavily charged with feathers they are in part stripped therefrom by the rakes 5, 5^a, the feathers adhering to these rakes being in turn given off to forks insufficiently charged as they pass said rakes. An even distribution is thereby effected. The feathers then drop to the bottom of receptacle 7, whence they are drawn through the conduit 11 by the blower A² and transferred through pipe 12 to the spreader B the deflecting plates 14^a, 14^b serving to spread them in an even layer onto the upper surface of the fabric from web F behind the toothed disks of the delivering roller 15^a which in suitably timed intervals delivers a portion of said layer between said fabric and the fabric from web F', the combined layers thence passing between the feed rollers 17 and 17^a and thence to the sewing mechanism C. The fabrics from webs F and F' and the combined sewed fabric are drawn forward over delivery roller 70 and stored on web F² (Figs. 1 and 2) by the following mechanism actuated from the sewing mechanism shaft 18: A screw or skew-gear-wheel 71 fixed to casing g' (Figs. 1, 2 and 9) meshes with skew gear-wheel 72 keyed to the shaft 73 bearing at its other extremity a skew-gear wheel 74 meshing with skew-gear wheel 75 fixed on the delivery roller 70. The delivery rollers 70 is thus caused to rotate in the direction of the arrow in unison with the sewing mechanism and, by frictional contact with the web F², it causes the same to rotate to take up the combined fabric as produced.

Where it is desired to manufacture composite materials comprising only one fabric layer with a superposed layer or layers of feathers, the web F' is discarded and the feathers are then fed onto the sheet fabric from web F alone, which thus forms a support for the feather layer.

In Fig. 12 is represented a modification of a feather distributing and loosening device embodying my invention and particu-

larly adapted for down and similar light and fluffy feathers whose great lightness and tendency to cohere and mass together causes considerable difficulties in separating and 5 properly distributing them. The parts of this distributing device differ from that represented in Figs. 1 and 2 in the following respects: Above the receptacle 7 at each side of the chute 8^a is arranged a supplemental 10 conveyer chain 40 each chain running over a pair of sprocket rollers 40^a, 40^b and provided at proper intervals with propelling pins 41 projecting from the chain and adapted to enter the spaces between the grate- 15 bars 6 forming the inclosure at the lower end of the said chute. When the said chains are in motion the said pins 41 sweep the feathers which tend to lag behind and adhere to the chute down onto the forks 3 of 20 the conveyers 2 arranged immediately below the conveyer chains 40, 40. The lower end of the chute 8^a is downwardly flaring and the conveyer chains 40, 40 are arranged parallel thereto, as shown. Thereby the mass 25 of feathers as it descends is allowed to expand and their ready descent is facilitated. For the same purpose the front and back of the lower end of said chute 8^a, as well as the sides are open worked or formed of grate 30 bars and downwardly flaring, as shown. To regulate the rate of feed of the feathers, a horizontal grate 42, also shown enlarged and in plan in Fig. 13, is arranged between the upper sprocket-wheels 2^a, 2^b, said grate being 35 made vertically adjustable by means of a slot 42^a and set screws 42^b, passing through said slot into the grate. The bars of the grate 42 extend between the paths of the carrying forks 3 thereby definitely limiting 40 the amount of material which each fork can carry forward from the receptacle past the said grate. At the lower contracted portion of the receptacle 7 is mounted a nozzle 43 through which air may be injected and 45 opposite the same in the said receptacle is arranged a curved deflecting plate 44. By this means eddy currents are produced and directed downward so as to disperse the feathers as they are drawn from the descending forks by the suction apparatus.

In Figs. 14 and 15 I have represented in sectional side-elevation and plan, respectively, a modified apparatus embodying my invention for the purpose of making a layer 55 fabric in which two layers, one consisting of down or similar fine material and the other of coarser material, such as stripped wing feathers, are combined with a supporting web fabric or two such fabrics inclosing the 60 feather-layers. In this apparatus two feather receptacles 45 and 46 arranged in series or one behind the other are provided, into which the feathers are fed by a blast through the pipes 45^a and 46^a, respectively. 65 At the lower extremities of the receptacles

45 and 46 are arranged the rotary delivering rollers 47 and 48, respectively, as shown in Fig. 14. The receptacle 46 which receives the light material having a tendency to lag is equipped at its lower portion with the 70 propelling chains 49, 49 provided with projecting pins 49^a at suitable intervals, which enter sides of the receptacle 46 through the spaces between the grate-bars there arranged similarly to the pins 41 in Fig. 12. Thereby 75 the feathers are positively urged downward toward the delivery roller 48. The receptacle 45 for the coarser material is provided at one side with a rake 45^b whose tines point toward the side opening at the lower portion 80 of the receptacle and which is adjustable in height by a slot 45^c arranged at its upper shank and a set screw 45^d engaging said slot and threaded into the wall of the receptacle. By adjusting the height of this rake the 85 quantity of material drawn from the receptacle by the delivery-roller 47 is determined.

The delivery and spreading roller 48 for the light material is a pneumatic delivering 90 device and for this purpose it is hollow, a portion of its surface at 48^a being provided with a number of perforations, and communicates with a pump through a pipe 48^b leading from one of its journals to said 95 pump. Said pipe 48^b fits into the roller 48 and its periphery is cut away at its upper portion opposite the inlet from the receptacle. The parts are so arranged that when the pump creates a suction the perforated 100 segment of cylinder 48 registers with the lower opening of receptacle 46 and a portion of the feathers are caused to adhere to the cylinder. When the perforated segment of the cylinder in its further rotation has 105 passed the lower opening of the receptacle 46, thereby closing the pipe 48^b by covering up its cut-away portion, the parts are so timed that the pump begins to force air into the cylinder and the material is delivered 110 and spread onto the material or fabric from the web F passing below the receptacle.

The delivery device for the forward receptacle 45 consists of an eccentrically journaled roller 47 which, as shown, is provided 115 with hooked needles 47^a at the portion of the roller most removed from the center of rotation and occupying about one fourth of its periphery. As the needles pass the lower opening they carry away a portion of the 120 feathers in said receptacle the rate of such delivery being governed by the length of the needles. This second layer of feathers is thus deposited on the layer of lighter feathers coming from the receptacle 46, and the 125 double layer of feathers with the fabric from the web F forming a support for the same is fed to the sewing mechanism C in the same manner as in the form of apparatus disclosed in Figs. 1 and 2. In case 130

the feather layers are to be inclosed between two fabric layers, a second sheet of fabric from web F' is delivered over the feed roller 17 on top of the feather layer and to the sewing mechanism.

In other respects this modification is the same as that described in connection with Figs. 1 and 2 except as regards the transmitting mechanism designed to govern the 10 rate of delivery of the feathers by the speed of the sewing mechanism shaft 18. This transmitting mechanism is represented in Fig. 15. From the shaft 49^a of the receiving drum 49^b for the composite fabric leaving 15 the sewing mechanism, which shaft is rotated from the shaft g of the friction-clutch device G actuated from the sewing mechanism shaft 18 as hereinbefore described, by a chain 50 running over sprocket wheels 51 20 and 52 keyed to shaft g and 49^c, respectively, a bevel gear wheel 53, meshing with bevel gear wheel 54 is actuated by means of a chain 55 running over sprocket wheels 56 and 57 mounted on shaft 49^c and on bearing 58, 25 respectively. The bevel gear 54 is fixed to the shaft 59^a of the friction wheel 59 bearing against a friction disk 60 keyed to the shaft 47^a of the delivery-roller 47. By this intermediate mechanism rotation is imparted 30 from the sewing machine shaft to the delivery-roller 47 and also to the delivery-roller 48 by the chain 61 running over sprocket wheels fixed to the shaft 47^a and 48^a of the rollers 47 and 48. In order to 35 vary the rate of delivery of the rollers 47 and 48, for a given speed of the sewing machine shaft, the friction roller 59 may be shifted radially with respect to the center of the disk 60 in any well known manner, 40 such for example as that shown in Fig. 12, where the said friction wheel is splined on the shaft 59^a so as to be longitudinally shiftable, though fixed against rotation on said shaft and is adapted to be shifted by a fork 45 or arm 64 engaging an annular groove formed in collar 59^b of the friction roller, the fork or arm being threaded on the spindle 62 journaled in bearings 62^a, 62^b and provided with a crank or pilot-wheel 63. 50 By turning said crank-wheel in one or the other direction the fork 64 is shifted, thereby causing the friction roller 59 to advance to or to recede from the center of the friction disk 60, thus correspondingly diminishing 55 or increasing the angular speed of the delivery rollers 45 and 46, and hence the thickness of the feather layers deposited onto the supporting fabric.

I claim:—

60 1. In an apparatus for making composite fabric, a receptacle for feathers and means arranged in connection with the same for loosening and separating the feathers, in combination with means for feeding a fabric 65 layer and a device for spreading the feathers

in an even layer onto the fabric layer, a blast for transferring the feathers from the loosening and separating device to the spreading device and means for connecting the feathers to the fabric layer arranged in advance of the spreading device.

2. In an apparatus for making composite fabrics, a blast for propelling feathers, in combination with a spreader casing interiorly provided with deflecting plates arranged to direct the feathers in part to the outer portions of the casing.

3. In an apparatus for making composite fabrics, a blast for propelling feathers, in combination with a spreader casing 75 interiorly provided with deflecting plates, secured one to the upper wall and one to the lower wall of the spreader casing, each extending partly to the opposite wall and arranged to direct the feathers in part to the 80 outer portions of the casing.

4. In an apparatus for making composite fabrics, a blast for propelling feathers, in combination with a spreader casing, horizontally flaring and vertically tapering in the 90 direction of the blast, said casing being interiorly provided with deflecting plates secured respectively to the upper and the lower casing wall and extending partly to the opposite casing wall, said deflecting plates being arranged to direct the feathers in part toward the outer portions of the casing to spread the 95 feathers in an even layer.

5. In an apparatus for making composite fabrics, a blast for propelling feathers, in 100 combination with a spreader casing horizontally flaring and vertically tapering in the direction of the blast, said casing being interiorly provided with deflecting plates, arranged to direct the feathers in part toward 105 the outer portions of the casing, a gang of toothed disks arranged in advance of the deflectors and means to rotate the said disks step-by-step, so as to periodically release a portion of the spread feather layer.

6. In an apparatus for making composite fabrics, a blast for propelling feathers, a spreader casing in advance of the same and interiorly provided with deflecting plates arranged to partly direct the feathers toward 115 the other portions of the casing, in combination with an arresting device arranged in advance of the deflecting plates, means for periodically releasing the arresting device, to liberate the spread layer of feathers, fabric 120 connecting means arranged in advance of the arresting device and means for feeding a fabric layer to the connecting means, arranged to receive the layer of spread feathers.

7. In an apparatus for making composite fabrics, a blast for propelling feathers, a spreader casing in advance of the same and interiorly provided with deflecting devices arranged to partly direct the feathers to- 125 130

ward the outer portions of the casing, in combination with a gang of toothed disks, arranged at the mouth of the casing, means for rotating said disks step-by-step to periodically release a portion of the spread feather layer, a sewing mechanism arranged in advance of the disks and means for feeding fabric layers to the sewing mechanism and in advance of the disks.

10 8. In an apparatus for making composite fabrics, a receptacle for feathers and means arranged in connection with the same for loosening and separating the feathers, a blast for propelling the separated feathers and a spreader casing in advance of the blast and provided interiorly with deflectors for evenly spreading the feathers in the casing, an arresting device in advance of the deflectors and means for periodically releasing 20 the same, in combination with sewing mechanism arranged in advance of the arresting device and means for feeding fabric layers to the sewing mechanism and directing the released feather layer between said fabric 25 layers.

9. In combination with a feather propelling air blast device, a spreader casing arranged in advance of the same the upper and lower walls of said casing being provided 30 with longitudinal ribs at the forward portion of said casing said upper casing wall being adjustable in height so as to enable the size of the exit opening to be varied.

10. In an apparatus for making composite fabrics, a receptacle for feathers, in combination with a conveyer extending into the receptacle and provided at intervals with separating forks each adapted to loosen the feathers and to remove a portion of the 40 same from the receptacle.

11. In an apparatus for making composite fabrics, a receptacle for feathers, in combination with a pair of downwardly convergent conveyers extending into the receptacle, each conveyer being provided at intervals with separating forks each adapted to loosen the feathers and to remove a portion of the same from the receptacle.

12. In an apparatus for making composite fabrics, a receptacle for feathers, in combination with a pair of downwardly convergent conveyers extending into the receptacle and so arranged that the inner portions of said conveyers travel upward from their 55 lowermost point and then outward and downward, said conveyers being provided at intervals with separating forks each adapted to loosen the feathers and to remove them in portions.

60 13. In an apparatus for making composite fabrics, a receptacle for feathers, in combination with a pair of downwardly convergent conveyers extending into the receptacle, said conveyers each mounted on a pair of 65 actuating pulleys of which the lower are

less in diameter than the upper pulleys, and separating forks mounted substantially perpendicularly on the conveyers at intervals.

14. In an apparatus for making composite fabrics, a receptacle for feathers, a spreader casing and a blast arranged between the same, in combination with a pair of downwardly extending conveyers provided at intervals with separating forks for loosening the feathers and to remove a portion of the same and transfer them to the blast.

15. In an apparatus for making composite fabrics, a receptacle for feathers, a spreader casing and a blast arranged between the receptacle and the spreader casing, in combination with a pair of conveyers extending into the receptacle, pulleys for actuating said conveyers and intermittent gearing arranged between said pulleys; a periodical stop device arranged at the forward portion of the spreader casing and means for actuating the same, and connecting means between the said actuating means and one of the conveyer actuating pulleys. 90

16. In an apparatus for making composite fabrics, a receptacle for feathers and a conveyer for the feathers extending into the receptacle and provided at intervals with feather separating and conveying forks in combination with vertically adjustable grate bars, arranged above the receptacle, extending into the same at their ends and adapted to regulate the amount of feathers carried forward by the conveyer, and a rake arranged below the grate bars and in proximity to the upper portion of the conveyer, and adapted to remove a part of the feathers from excessively charged conveying forks and to supply them to forks insufficiently charged as they pass the said rakes. 100

17. In an apparatus for making composite fabrics, a receptacle for feathers and a hopper above the same and provided with openings at opposite sides, a vertically adjustable series of grate bars arranged in each of said openings, in combination with a pair of conveyers within the receptacle arranged to travel past and in proximity to the ends of the grate bars and provided at 110 intervals with feather separating and conveying forks, and a rake arranged below and in proximity to the lower ends of each series of grate bars.

18. In an apparatus for making composite fabrics, a receptacle for feathers and a hopper above the same and provided with openings at opposite sides, a downwardly flaring series of grate-bars arranged in said openings, in combination with a pair of conveyers within the receptacle arranged to travel past and in proximity to the ends of the grate-bars and provided at intervals with feather separating and conveying forks. 125

19. In an apparatus for making composite 130

fabrics, a receptacle for feathers having an open side in combination with a conveyer arranged in proximity to said open side and provided at intervals with projecting pins arranged to enter the opening in the side of the receptacle into contact with the feathers.

20. In an apparatus for making composite fabrics, a receptacle for feathers having 10 openings at opposite sides, said openings being provided with grate-bars, in combination with a pair of conveyers one arranged in proximity to each opening and each provided at intervals with projecting 15 propelling pins adapted to enter the receptacle between the grate-bars.

21. In an apparatus for making composite fabrics, a receptacle for feathers and a conveyer provided with feather-carrying and 20 loosening forks projecting from the conveyer at intervals arranged in the receptacle, in combination with a grate arranged in the receptacle, the grate-bars of the said grate extending between the paths of the said 25 forks.

22. In an apparatus for making composite fabrics, a receptacle for feathers and a conveyer provided with feather-carrying and loosening forks projecting from the 30 conveyer at intervals, in combination with a vertically adjustable, substantially horizontal grate arranged within the receptacle, the grate-bars of the said grate extending between the paths of said forks.

23. In an apparatus for making composite fabrics, a receptacle for feathers, means for 35 loosening and conveying said feathers to an advanced part of the receptacle and a conduit leading therefrom to a blast, in combination with an air injecting nozzle 40 at said advanced part of the receptacle and a deflecting plate arranged opposite the same, whereby the feathers are subjected to eddy currents to further loosen them before 45 entering the blast conduit.

24. In an apparatus for making composite fabrics, a pair of feather-receptacles arranged in series and provided with delivering rollers at their bottoms in combination with means for feeding a sheet of fabric 50 below the receptacles, and sewing mechanism arranged in advance of said receptacles.

25. In an apparatus for making composite fabrics, a pair of feather receptacles arranged in series, one receptacle being provided at its bottom with an eccentric roller provided at the portion of its periphery most removed from the center of rotation with needles and the other receptacle with 60 a pneumatic delivery roller, in combination with means for feeding a sheet of fabric below the receptacles and a sewing mechanism in advance of said receptacles.

26. In an apparatus for making composite 65 fabrics, a pair of feather receptacles, each receptacle being provided with delivering rollers at its bottom, in combination with means for feeding a sheet of fabric below the receptacles, a sewing mechanism in advance of said receptacles and means for varying the speed of the delivery rollers with respect to the speed of the sewing mechanism.

27. In an apparatus for making composite 75 fabrics, a feather receptacle in combination with an eccentric delivery roller arranged at the bottom of the same, said roller being provided at a portion of the periphery most remote from the center of rotation, with 80 needles adapted to enter the receptacle, and a rake arranged in proximity to a lower side opening in said receptacle.

In testimony whereof I affix my signature in presence of two witnesses.

FRITZ WEVER.
